UNITED STATES PATENT OFFICE.

AARON E. SIPE, OF BUFFALO, NEW YORK.

DESIGN FOR A BADGE.

SPECIFICATION forming part of Design No. 30,303, dated March 7, 1899.

Application filed February 10, 1899. Serial No. 705,206. Term of patent 8½ years.

To all whom it may concern:

Be it known that I, AARON E. SIPE, a citizen of the United States, residing at Buffalo, in the county of Erie and State of New York, have 5 invented and produced a new and original Design for a Badge or Similar Article, of which the following is a specification, reference being had to the accompanying drawing, forming a part thereof.

10 This design relates to the configuration and ornamentation of a badge or similar article.

The accompanying drawing is a face view of a badge embodying my design.

The leading feature of my design consists of the representation of a terrestrial globe A, 15 surmounted by the figure of a buffalo B.

What I claim as new is—

The design for a badge or similar article, substantially as herein shown and described.

Witness my hand this 8th day of February, 1899.

AARON E. SIPE.
